Primary Examiner — W. A. Teddy Falloway

(57) CLAIM

The ornamental design for a solar gnome statue as shown and described.

DESCRIPTION

FIG. 1 is a top perspective view of a solar gnome statue showing my new design;

FIG. 2 is a bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The broken lines illustrate portions of the solar gnome statue that form no part of the claimed design.
